[57] CLAIM

The ornamental design for a combined stackable and nestable bin, as shown.

DESCRIPTION

FIG. 1 is a perspective view of a combined stackable and nestable bin showing my new design,

FIG. 2 is a front elevational view,

FIG. 3 is a top plan view,

FIG. 4 is a bottom plan view,

FIG. 5 is a right hand side elevational view, the opposite side being a mirror image thereof, and

FIG. 6 is a rear elevational view.

FIG. 1

FIG. 2

FIG. 3

FIG. 4

FIG. 5

FIG. 6
